Atty.

UNITED STATES PATENT OFFICE

WILHELM MORELL, OF LEIPZIG, GERMANY

SPEEDOMETER

Application filed November 12, 1928, Serial No. 318,728, and in Germany November 15, 1927.

My invention relates to speedometers in which a plurality of gearings, each corresponding to a definite range of measurements, are provided and arranged to be rendered operative as desired.

It is an object of my invention to improve a speedometer of this type. To this end I provide a change-speed gear and means rotatably carried on the speedometer casing for throwing in the gearings corresponding to the several ranges of measurements or speeds of the change-speed gear, by rotating such means.

Heretofore the change from one speed to another was effected by axial displacement. By providing a change-speed gear as described, and by changing the speeds through the medium of a rotary part, the size of the instrument is reduced and its operation, maintenance and manufacture are simplified and facilitated.

In a preferred embodiment of my invention the driving shaft is supported eccentrically in a cap which conceals the gears of the change-speed gear, and a pinion is secured on the driving shaft within the cap. By rotating the cap the pinion is alternately placed in operative relation to the several sets of wheels constituting the change-speed gear.

In the drawing affixed to this specification and forming a part thereof a hand-speedometer embodying my invention is illustrated diagrammatically by way of example:

In the drawing
35 Fig. 1 is an end elevation, and

Fig. 2 is a side elevation, the parts in which the gearing is housed being shown in section.

Figs. 3 and 4 are sections on the lines A—B and C—D in Fig. 1, respectively.

40 Referring to the drawing, 3 is the foundation plate of the instrument on which the several parts constituting the speedometer unit are mounted. These parts need not be described in detail as they are of the usual design.

45 4 is the main shaft of the instrument, 1 is a pinion on the main shaft and 8, 9 and 10 are gears which are in permanent mesh with the pinion 1 on the main shaft 4. 13, 14 and 15 are gears on shafts 5, 6 and 7, respectively, the

shafts being carried in the foundation plate 3 and the parallel plate 3a which is connected with the plate 3 by stays 3b. 11 is a cap which is rotatably carried on the plates 3 and 3a, 12 is a soldered sleeve, connecting the cap 55 11 with the casing of the instrument, and 16 is a driving shaft which is eccentrically supported in a boss of the cap 11, the parallel plate 3a being centrally recessed for the reception of the boss. 2 is a pinion on the inner end of shaft 1 which is adapted to alternately engage the gears 13, 14 and 15 upon rotation of the cap 11.

It will be understood that upon rotation of the cap 11 the pinion 2 is bodily rotated 65 on a circular path at a tangent to the pitch circles of the wheels 13, 14 and 15. Consequently, upon rotating the cap 11, the pinion 2 will be placed in mesh with one of the gears 13, 14 and 15, as desired, and it is possible 70 to set the speedometer for the desired range of measurements, or speed of the change-speed gear, on the shortest way by rotating the cap 11 to the left or to the right, as required.

The instrument does not require for its 75 operation any other means beside the cap 11 and the gearings which would be required in any case, and is readily manufactured as the cap 11 and the means by which it is held on the instrument, are simple rotary elements.

The length of the novel speedometer is only about two thirds, as compared with the instruments referred to in the introduction, in which the range of measurements is varied 85 by axial displacement.

It is to be understood that I am not limited to a change-speed gear having three speeds as described but that I may provide any number of speeds.

I wish it to be understood that I do not desire to be limited to the exact details of construction shown and described for obvious modifications will occur to a person skilled in the art.

In the claim affixed to this specification no selection of any particular modification of the invention is intended to the exclusion of other modifications thereof and the right to subsequently make claim to any modification 95 100

not covered by this claim is expressly reserved.

I claim:—

5 A hand-speedometer for several ranges of measurements comprising a principal plate, a principal shaft mounted to rotate in said plate, a pinion on said principal shaft, an auxiliary plate spaced apart from, and connected with, said principal plate, a gearing organization including a plurality of lay shafts, one shaft per range, supported in said principal and auxiliary plates, a pair of gear wheels on each lay shaft, one gear wheel in each pair meshing permanently with the pinion on said 10 principal shaft, a casing mounted to rotate about the axis of said principal shaft and surrounding said gearing organization, a driving shaft mounted to rotate in said casing eccentrically with respect to the axis of 15 said principal shaft, and a pinion on said driving shaft adapted to be moved into mesh with those gear wheels on said lay shafts which are not in permanent mesh with the pinion on said principal shaft, as said casing 20 is rotated about the axis of said principal shaft.

In testimony whereof I affix my signature.

WILHELM MORELL.
